WILLIAM M. KRICKBAUM, OF CLEVELAND HEIGHTS, OHIO, ASSIGNOR TO THE GRASSELLI CHEMICAL COMPANY, OF CLEVELAND, OHIO, A CORPORATION OF OHIO.

FURNACE FOR MAKING HYDROCHLORIC ACID AND THE LIKE.

1,167,763.

Specification of Letters Patent. Patented Jan. 11, 1916.

Application filed June 17, 1915. Serial No. 34,589.

To all whom it may concern:

Be it known that I, WILLIAM M. KRICKBAUM, a citizen of the United States, and a resident of Cleveland Heights, county of 5 Cuyahoga, and State of Ohio, have invented a new and useful Improvement in Furnaces for Making Hydrochloric Acid and the like, of which the following is a specification, the principle of the invention being herein explained and the best mode in which I have contemplated applying that principle, so as to distinguish it from other inventions.

The present improved furnace, while designed more especially for the manufacture 15 of hydrochloric acid by the familiar method of reacting between sodium chlorid and sulfuric acid, is not necessarily limited to this particular use, but may find general employment in any connection where a similar re- 20 action of calcining operation requiring the operation of heat, is involved.

The object of the invention is to provide a furnace of the type in question in which the desired operation may be carried on continu- 25 ously, one stage following the other immediately without any interruption and without its being necessary to transfer the material.

A further object is so to mount or support the operating parts of the furnace, as well 30 as so to arrange the means for supplying material to the furnace, as will prevent damage occurring to such operating parts by contact therewith to a minimum of the material being treated.

To the accomplishment of the foregoing 35 and related ends, the invention, then, consists of the means hereinafter fully described and particularly pointed out in the claims.

The annexed drawings and the following 40 description set forth in detail certain mechanism embodying the invention, such disclosed means constituting, however, but one of various mechanical forms in which the principle of the invention may be used.

In said annexed drawings: Figure 1 is a 45 horizontal section of my improved furnace, the plane of the section being indicated by the line 1—1, Fig. 2; Fig. 2 is a vertical section of such furnace, the plane of such section being indicated by the line 2—2, Fig. 1; Fig. 3 is another vertical section at right angles to that of Fig. 2, the plane thereof

being indicated by line 3—3, Fig. 2; Fig. 4 is a detail partly in section illustrating the construction and method of mounting the 55 plows or scrapers which constitute a feature of the operating mechanism; Fig. 5 is a transverse section of such a plow or scraper as indicated by the line 5—5, Fig. 4; Fig. 6 is a front elevation of a plow or scraper 60 similar to that of Fig. 5; and Figs. 7 and 8 are views similar to Fig. 6, but illustrating two other forms of such plow or scraper also used in the furnace.

The working or furnace chamber 1 65 proper, is of circular outline in a horizontal plane, as indicated in Fig. 1, and is relatively low compared with the diameter. The top 2 and side walls 3 of such chamber are formed of fire brick, or equivalent refractory 70 material, while the bottom or floor consists of a shallow pot 4 at the center surrounded by a peripheral calcining bed 5, both such pot and bed being preferably constructed of iron. The bed 5 is moreover a sectional construction, being made of a series of seg- 75 mental plates, as indicated in part in Fig. 1. A pair of suitable fire boxes 6 are arranged to one side of the furnace chamber with grates and other appurtenances, the flues 80 therefrom communicating with a heating chamber 8 lying immediately above the roof of the furnace chamber 1 proper, and thence communicating by means of other vertical flues 9, at the opposite side of the structure, 85 with an annular heating chamber 10 lying directly beneath the calcining bed 5, and communicating with a discharge flue 11 leading to the stack. Laterally surrounded by the annular chamber 10, thus lying under 90 the decomposing pot, is a circular heating chamber 12, separated therefrom by a partition 13 having perforations 14 allowing of a limited communication between the two, such circular chamber lying directly beneath 95 the pot 4 that forms the central portion of the furnace floor. The material to be treated in the furnace is supplied, as will be presently described, to this central pot, and spread evenly over such pot and stirred, at 100 the same time being gradually moved toward the edge of the pot and thence outwardly across and toward the edge of the annular calcining bed. For the purpose

of thus stirring and moving the material in question, a series of shovels or plows are provided, the same being attached to radial arms 15, preferably four in number, disposed ninety degrees apart, which are carried by the upper end of a vertical shaft 16, that rises centrally through the pot, as shown in Figs. 2 and 3, such pot being formed with a boss 17, that forms a bearing for the upper end of such shaft. The lower end of the latter is suitably journaled in a bearing (not shown), and appropriate driving means (also not shown), are connected therewith, whereby it may be rotated at the desired rate of speed, correspondingly rotating the radially extending arms. The construction of the shovels or plows carried by these arms, while in the main the same, differs slightly in the case of those 18, which operate in the pan 3 from those 19 operating in the annular bed, in that the former are larger and less numerous than the latter, the form of construction being such that the material in the pot is moved radially outward toward the edge of the pot, and onto the calcining bed proper more rapidly than it is thereupon moved across such bed to the latter's outer edge.

Figs. 4, 5 and 6 illustrate one of the shovels 19, while Fig. 7 shows one of the shovels 18. The radial arms 15 are preferably of the Z cross-section appearing in said Fig. 4, and the stems 20 wherewith the shovels are provided, are secured to said arms by means of bolts 21, which permit of the vertical adjustment of the shovels, as will be readily understood.

At suitable points about said bed 5, preferably at two diametrically opposite points as illustrated in Figs. 1 and 2, chutes 22 are provided, the upper ends of which intersect the bed so that the material, as it is gradually worked toward the edge of the latter by the plows, may be automatically discharged into these chutes. Such discharge is facilitated by attaching to one or more of the arms 15, at the extreme outer end, a special scraper-like shovel 23. (See Figs. 2 and 8.) Gates 24 may be provided on the chutes so that the latter may be allowed to accumulate a predetermined amount of the calcined material thus discharged into them before they are emptied, and so that the trucks or like receptacles, need only be brought up to the chutes at intervals. At another suitable point in the furnace structure, as for example midway between these two discharge points, a lateral opening 25 leading into the furnace chamber is provided in order to permit inspection of the interior, while the operation is progressing, as also to permit of the introduction of a poker, rake or like implement, should this become necessary. This opening, as well as the corresponding openings 26 provided in conjunction with

the chutes 22, are of course normally closed. The gases or vapor arising from the reaction, taking place in the chamber, are designed to be conducted away through a conduit 26 in the upper wall or roof thereof, 70 as shown in Fig. 1.

For supplying the material to the furnace pot as previously explained, a suitable feeding mechanism is provided, consisting of a horizontal cylindrical chamber 30 with a hopper 31 at one end and a suitable screw 32, or equivalent feeding device, whereby the material is discharged onto a chute 33 extending downwardly to a central point in the chamber, directly over the shaft, where such material is in turn received by a second chute 34 mounted on the upper end of the shaft and disposed to finally discharge the material into the pot between two adjacent arms 15, as indicated in Fig. 1. By 80 virtue of the foregoing arrangement, the material is prevented from dropping on the end of the shaft, or onto the arms, and is directly placed in the pot 4 at the most central point possible, where it is immediately 90 engaged by the inner shovels 18 on the arms and spread evenly over the pot and gradually worked toward the edge of the latter, as already described.

The general operation of the foregoing 95 apparatus, constituting my improved furnace, should be readily apparent. It will be understood that the two fire-boxes 6 will ordinarily be used at the same time, although one may be shut down for repairs so that 100 uninterrupted operation may be had. The heated gases arising from either grate are conducted, as already explained, first across the top of the furnace chamber proper, thence underneath the annular calcining bed 105 5 to the stack 11. Incidentally the chamber 12 beneath the pot 4 will also be heated, but not to as high a temperature as the calcining bed, the number and size of the openings 110 14 in the partition 13 being designed to impart just the proper temperature to such pot for carrying on therein the initial reaction, or stage of treatment. In the case of the manufacture of hydrochloric acid, this reaction proceeds fairly rapidly and thereafter the slower calcining operation follows, 115 so that, while the material is moved out of the pot relatively promptly after its admission thereto, it is carried more slowly across the hotter annular bed beyond, and the reaction thus entirely completed by the time such material reaches the outer edge of such bed and is discharged.

The foregoing construction and arrangement permits the use of an integral pot to 120 receive the material in its initial semi-liquid, or pasty state, and a built-up or segmental bed on which to conduct the calcining operation, while the arrangement of flues and heating chambers surrounding the chamber 125 130

proper is such as to impart exactly the right temperature, to each part of the furnace floor. By means of such furnace, accordingly, I have found in actual practice that 5 the production of hydrochloric acid may be carried on continuously and with the utmost expedition possible, having regard to the reaction involved. At the same time, all the operative parts are kept relatively clear of 10 the material that they handle, so that the likelihood of such mechanism becoming clogged up is minimized, and the completion of the reaction insured within the limits of the chamber. The compactness of the 15 structure as a whole and the accessibility of all its different parts are additional commendable features.

Other modes of applying the principle 20 of my invention may be employed instead of the one explained, change being made as regards the mechanism herein disclosed, provided the means stated by any of the following claims or the equivalent of such stated means be employed.

25 I therefore particularly point out and distinctly claim as my invention:—

1. In a furnace for making hydrochloric acid and the like, the combination with a working chamber having a floor adapted to 30 receive the material to be operated upon; of heating chambers located beneath such floor, said heating chambers being arranged to impart different degrees of heat to different parts of such floor, substantially as 35 described.

2. In a furnace for making hydrochloric acid and the like, the combination with a working chamber having a floor adapted to receive the material to be operated upon: 40 of a heating chamber located above said working chamber; and other heating chambers located beneath such floor, said heating chambers being arranged to impart different degrees of heat to different parts of such floor, substantially as described.

3. In a furnace for making hydrochloric acid and the like, the combination with a substantially circular working chamber having a floor adapted to receive the material 50 to be operated upon; of a circular heating chamber located centrally beneath such floor; and an annular heating chamber beneath the outer portion of such floor, the heated gases passing directly through such 55 annular chamber, and said circular chamber having limited communication with said annular chamber, whereby the portion of such floor over the latter is more highly heated than the central portion of such floor.

60 4. In a furnace for making hydrochloric acid and the like, the combination with a substantially circular working chamber having a floor adapted to receive the material to be operated upon; of a heating chamber 65 located above said working chamber; an-

other circular heating chamber located centrally beneath such floor; and an annular heating chamber beneath the outer portion of such floor, the heated gases passing directly through such annular chamber, and 70 said circular chamber having limited communication with said annular chamber, whereby the portion of such floor over the latter is more highly heated than the central portion of such floor.

75 5. In a furnace for making hydrochloric acid and the like, the combination with a substantially circular working chamber, a shallow pot forming the central portion of the floor of said chamber, and an annular calcining bed surrounding said pot; of a circular heating chamber located beneath said pot; and an annular heating chamber located beneath said bed, the heated gases 80 passing directly through such annular chamber, and said circular chamber having limited communication with said annular chamber, whereby said bed is more highly heated than said pot.

85 6. In a furnace for making hydrochloric acid and the like, the combination with a substantially circular working chamber, a shallow pot forming the central portion of the floor of said chamber, and an annular calcining bed, made up of segmental plates 90 surrounding said pot; of a heating chamber located above said working chamber; another circular heating chamber located beneath said pot; and an annular heating chamber located beneath said bed, the heated gases 95 passing directly through such annular chamber, and said circular chamber having limited communication with said annular chamber, whereby said bed is more highly heated than said pot.

100 7. In a furnace for making hydrochloric acid and the like, the combination with a working chamber having a floor adapted to receive the material to be operated upon; of heating chambers located beneath such 105 floor, said heating chambers being arranged to impart different degrees of heat to different parts of such floor; and means adapted to remove the material across such floor from one such part to the other thereof.

110 8. In a furnace for making hydrochloric acid and the like, the combination with a working chamber having a floor adapted to receive the material to be operated upon; of heating chambers located beneath such 115 floor, said heating chambers being arranged to impart different degrees of heat to different parts of such floor; and means adapted, to move the material across such floor from one such part to the other thereof, but 120 at different rates of speed across such parts, respectively.

125 9. In a furnace for making hydrochloric acid and the like, the combination with a working chamber having a floor adapted to 130

receive the material to be operated upon; of heating chambers located beneath such floor, said heating chambers being arranged to impart different degrees of heat to different parts of such floor; and means adapted to remove the material across such floor from one such part to the other thereof, but more rapidly across the less highly heated than across the more highly heated part.

10 10. In a furnace for making hydrochloric acid and the like, the combination with a substantially circular working chamber, a shallow pot forming the central portion of the floor of said chamber, and an annular calcining bed surrounding said pot; of a circular heating chamber located beneath said pot; an annular heating chamber located beneath said bed, the heated gases passing directly through such annular chamber, and said circular chamber having limited communication with said annular chamber, whereby said bed is more highly heated than said pot; and means adapted to move the material from said pot to said bed and then across the latter.

11. In a furnace for making hydrochloric acid and the like, the combination with a substantially circular working chamber, a shallow pot forming the central portion of the floor of said chamber, and an annular calcining bed surrounding said pot; of a circular heating chamber located beneath said pot; an annular heating chamber located beneath said bed, the heated gases passing directly through such annular chamber, and said circular chamber having limited communication with said annular chamber, whereby said bed is more highly heated than said pot; and means adapted to move the material from said pot to said bed and then across the latter, said means operating thus to move the material more rapidly from said pot to said bed than across the latter.

12. In a furnace for making hydrochloric acid and the like, the combination with a substantially circular working chamber, a shallow pot forming the central portion of the floor of said chamber, and an annular calcining bed surrounding said pot; of a circular heating chamber located beneath said pot; an annular heating chamber located beneath said bed, the heated gases passing directly through such annular chamber, and said circular chamber having limited communication with said annular chamber, whereby said bed is more highly heated than said pot; and means adapted to move the material from said pot to said bed and then across the latter, said means including a vertical rotatable shaft, projecting centrally through said pot, a radial arm on said shaft extending to substantially the periphery of said working chamber, and a plural-

ity of shovels carried by said arm, and adapted to engage the floor of said chamber. 65

13. In a furnace for making hydrochloric acid and the like, the combination with a substantially circular working chamber, a shallow pot forming the central portion of the floor of said chamber, and an annular calcining bed surrounding said pot; of a circular heating chamber located beneath said pot; an annular heating chamber located beneath said bed, the heated gases passing directly through such annular chamber, and said circular chamber having limited communication with said annular chamber, whereby said bed is more highly heated than said pot; and means adapted to move the material from said pot to said bed and then across the latter, said means including a vertical rotatable shaft, projecting centrally through said pot, a radial arm on said shaft extending to substantially the periphery of said working chamber, and a plurality of shovels carried by said arm, and adapted to engage the floor of said chamber, the shovels within said pot being adapted to move the material more rapidly onto said bed than the shovels on the latter transfer such material thereacross. 90

14. In a furnace for making hydrochloric acid and the like, the combination with a substantially circular working chamber, a shallow pot forming the central portion of the floor of said chamber, and an annular calcining bed surrounding said pot; of a circular heating chamber located beneath said pot; an annular heating chamber located beneath said bed, the heated gases passing directly through such annular chamber, and said circular chamber having limited communication with said annular chamber, whereby said bed is more highly heated than said pot; and means adapted to move the material from said pot to said bed and then across the latter, said means including a vertical rotatable shaft, projecting centrally through said pot, a radial arm on said shaft extending to substantially the periphery of said working chamber, and a plurality of shovels carried by said arm, and adapted to engage the floor of said chamber, the shovels within said pot being relatively large and inclined so as to move the material relatively rapidly from said pot onto said bed, and the shovels on said bed being relatively small and inclined so as to move such material relatively slowly across said bed. 115

15. In a furnace for making hydrochloric acid and the like, the combination with a substantially circular working chamber having a floor adapted to receive the material to be operated upon; of a heating chamber located beneath such floor; means adapted to move the material from the center toward

the periphery of such floor, said means including a vertical rotatable shaft projecting centrally through said pit, a series of radial arms on said shaft extending substantially to such periphery, and a plurality of shovels carried by said arms; and means adapted to feed material into said working chamber at approximately the center of such floor, said means including a chute carried by said shaft

and discharging onto the floor between two such arms, and another fixed chute discharging onto such first chute.

Signed by me, this 8th day of June, 1915.

WILLIAM M. KRICKBAUM.
